ICE-SCORING MACHINE

Edward L. Thibodeaux and Alvin J. Thibodeaux,
Demopolis, Ala.

Application September 23, 1948, Serial No. 50,818

4 Claims. (Cl. 125—14)

1

This invention relates to an ice scoring machine and particularly to a machine for scoring blocks of ice as they come from an ice machine, along predetermined spaced lines and has for an object the provision of a machine of the character designated which shall be simple of design and operation and easily manipulated.

A further object of our invention is to provide an ice scoring machine including spaced rotary saws mounted on parallel shafts together with means to move the apparatus to a stationary block of ice when scoring it.

More specific objects of our invention are to provide an ice scoring machine including spaced rotary saws mounted on parallel shafts with an improved housing, with safety guards for the saws mounted in the housing, to minimize accidents; to provide novel mounting means in which the saw housing is suspended from an overhead track with supporting rollers, whereby to shift the saws relative to a block of ice; and to provide means for driving the saws in opposite directions whereby to throw the ice cut by the saws rearwardly and to draw the saws into the block of ice being scored.

Apparatus embodying features of our invention is illustrated in the accompanying drawings forming a part of this application, in which:

Fig. 1 is a front elevational view;

Fig. 2 is a side elevational view;

Fig. 3 is a sectional view taken along the line III—III of Fig. 1;

Fig. 4 is an enlarged sectional view along the line IV—IV of Fig. 1;

Fig. 5 is a detail sectional view taken along line V—V of Fig. 2;

Fig. 6 is a side elevational view illustrating the operation of the machine in scoring a block of ice while standing on end;

Fig. 7 is a similar view illustrating the scoring of a block of ice lying on its side;

Fig. 8 is a view similar to Fig. 6 showing the further scoring of the block into smaller blocks; and,

Fig. 9 is a perspective view of the support for the block of ice.

Referring now to the drawings for a better understanding of our invention, and particularly to Figs. 1 to 5 inclusive thereof, our improved machine is comprised of a housing having semi-cylindrical sides 10 and 11 which are joined together in spaced relation at their upper ends by a cover 12 so as to be open at front and rear to straddle a block of ice as it comes from an ice making machine. The lower ends of the semi-cylindrical sides are closed by separate end members 13 and 14, which are not joined to each other.

Mounted above the housing is a track comprised of facing channel members 16 and 17.

2

The housing is suspended from the overhead track by means of a structural frame member 18 secured at its lower end to the housing 12 and which has a horizontal structural member 19 secured to its upper ends. Rigidly secured to the ends of the horizontal member 19 are hangers 21 and 22 which at their upper ends carry axles 23 on each of which are journaled rollers 24 and 26. See Fig. 5. The rollers 24 and 26 are of a diameter substantially equal to the width of the channels 16 and 17 whereby to prevent tilting of the machine in operation.

Extending longitudinally of the semi-cylindrical sides 10 and 11 of the housing are vertical shafts 27 and 28 which are mounted in suitable bearings in the ends of the housing, as shown. The shafts 27 and 28 are driven, respectively, by electric motors 29 and 31 which are mounted on the structural member 18. Mounted on the shafts 27 and 28, respectively, are upper opposed saws 32 and 33, and lower opposed saws 34 and 36. The saws 32 and 34 on the shaft 27, and the saws 33 and 36 on the shaft 28 are preferably spaced apart a distance equal to $\frac{1}{3}$ the length of a 300 pound block of ice as it comes from the ice machine. The motors 29 and 31 drive the saws in opposite directions as indicated by the arrows in Fig. 4 whereby they feed their way into a block of ice as will hereinafter be more fully explained.

The apparatus is pulled back and forth manually on the overhead track by means of a U-shaped handle 37 secured to an angle member 38 on the upper end 12 of the housing. Mounted to oscillate in front of the shafts 27 and 28 in the housing are rods 39 and 41 which extend from end to end of the housing and are journaled in the ends thereof. Mounted on the rods 39 and 41 in front of each of the saws 32, 33, 34 and 36, is a guard comprised of arcuate fingers 42 and 43 disposed immediately above and below the saw and in front thereof. Torsion springs 44 and 46 surrounding the rods 39 and 41 and anchored in the upper end member 12 of the housing normally hold the rods with their guards yieldingly in their forward positions. On the upper ends of the rods 39 and 41 are notches 47 and 48 which are engaged by detents 49 and 51 when the guards are in their forward positions and which hold them latched in that position until released. The detents 49 and 51 are carried by bars 52 and 53 which are pivoted, respectively, at 54 and 56 and which are provided with slotted overlapping ends at 57. A pull handle 58, accessible to the handle 37 for operating the machine, is disposed to be grasped by the operator when grasping the handle 37 to release the detents 49 and 51, whenever required. The pull handle 58 is held in its rearward or latching position, by means of a spring 59.

As before stated, the saws on each of the shafts are preferably spaced apart a distance equal to $\frac{1}{3}$ the length of a 300 pound block of ice as it comes from the ice machine. In operation, the block of ice 61 (see Fig. 6) is placed directly in front of the machine in a position so that the lower saws 34 and 36 may score it along a line 62 which is $\frac{1}{3}$ of the distance from the lower end of the block. The upper saws 32 and 33 at the same time score the block along a line 63 a distance $\frac{2}{3}$ of the length of the block. The block is thus scored along lines dividing it into three 100 pound blocks.

The block 61, scored along lines to divide it into three 100 pound blocks may then be turned on its side as shown in Fig. 7 onto a level support 64 which raises the block a sufficient distance for the lower saws 34 and 36 to score it along a line 66 which thus divides the three 100 pound blocks already provided into six 50 pound blocks.

If it be desired to further divide into 25 pound blocks, the upper 100 pound section A of the block is first removed and the remaining portions of the block are placed in a raised position shown in Fig. 8 whereby the lower portion of the block is scored along lines 67 and 68 to divide the 50 pound blocks into halves.

In order to raise the block to the position shown in Fig. 8 of the drawings, we preferably provide the level support 64 with an auxiliary block 69 which is hinged to the side thereof and which is of a thickness, when turned over to the position shown in Fig. 8, to raise the block of ice the required distance to subdivide the 50 pound block as shown in Fig. 7 into 25 pound blocks.

In the operation just described, the handle 37 of the machine is grasped by the operator and the pull member 58 releasing the detents 49 and 51 is simultaneously grasped by him to release the guards 42 and 43 on each of the saws. With the block of ice in front of the machine, the operator pulls it forwardly, the rotation of the saws being in opposite directions, as shown in Fig. 4, causes the saws to feed their way into the block of ice and to throw the ice cut by the saws rearwardly of the apparatus. As soon as the block has been scored along the lines such as 63 and 62, the apparatus is pushed rearwardly, manually, and if further cutting is to be done, the ice may be turned to the position shown in Figs. 7 and 8 as required.

In actual operation, we have found our improved apparatus effective to rapidly score blocks of ice. In the cutting operation, the machine is very easy to operate, as it feeds its way into the block of ice and once the scoring is done is easily pushed rearwardly out of the way. The direction of rotation of the saws is such that the ice cut by the saws is thrown to the rear out of the way of the operator and thus causes no hazard. Furthermore, the guards 42 and 43 in front of the saws are so mounted and held in position that danger therefrom to the operator is prevented.

While we have shown our invention in but one form, it will be obvious to those skilled in the art that it is not so limited, but is susceptible of various changes and modifications, without departing from the spirit thereof, and we desire, therefore, that only such limitations shall be placed thereupon as are specifically set forth in the appended claims.

What we claim is:

1. In an ice scoring machine, a pair of spaced vertically extending shafts, a pair of rotary saws on each shaft spaced to score a block of ice along predetermined lines, a housing for the shafts and saws having spaced semi-cylindrical sides partially encircling the saws and open front and rear to straddle a block of ice, an overhead horizontal supporting track for the housing, a rigid member extending upwardly from the housing, a horizontal arm on the rigid member, rollers coacting between the horizontal arm and the track, a handle on the upper end of the housing disposed to be grasped to move the housing and saws horizontally, rods mounted in the housing to oscillate in front of the saws, guard members on the rods above and below each of the saws, and springs for yieldably holding the guard members in front of the saws.

2. In an ice scoring machine, a pair of spaced vertically extending shafts, a pair of rotary saws on each shaft spaced to score a block of ice along predetermined lines, a housing for the shafts and saws having spaced semi-cylindrical sides partially encircling the saws and open front and rear to straddle a block of ice, an overhead horizontal supporting track for the housing, a rigid member extending upwardly from the housing, a horizontal arm on the rigid member, rollers coasting between the horizontal arm and the track, and a handle on the upper end of the housing disposed to be grasped to move the housing and saws horizontally, rods mounted in the housing to oscillate in front of the saws, guard members on the rods above and below each of the saws, springs for yieldably holding the guard members in front of the saws, a latch for each of the rods to hold the guard members against movement until released, and releasing means for the latches mounted adjacent the handle on the housing whereby to release the guards when sawing.

3. Apparatus as defined in claim 2 together with means to drive the saws in opposite directions to throw the shavings rearwardly of the saw and to draw the apparatus into the block of ice being sawed.

4. An ice scoring machine comprising spaced parallel vertically disposed saw shafts, a pair of spaced saws on each shaft, a housing for the shafts and the saws open at front and rear for the passage of a block of ice, a horizontal roller support for suspending the housing, a handle on the housing in position to be grasped to shift the housing and saws with respect to a block of ice, spring pressed guard fingers in front of each of the saws, latch means for detaining the fingers in guard position, and means accessible to the handles for releasing the latch means.
